UNITED STATES PATENT OFFICE.

HENRY C. JOHNSON, OF EL DORADO, ARKANSAS.

DESIGN FOR A BUCKLE.

SPECIFICATION forming part of Design No. 16,123, dated June 2, 1885.

Application filed April 24, 1885. Term of patent 14 years.

To all whom it may concern:

Be it known that I, HENRY C. JOHNSON, a citizen of the United States, residing at El Dorado, in the county of Union and State of Arkansas, have invented a new and original Design for Buckles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The accompanying drawings illustrate my new design for a buckle. Figure 1 is a perspective view of same. Fig. 2 is a longitudinal sectional view of same.

The design of my buckle consists of a flat plate, which forms the bottom *a*. The buckle also has two flat sides, *b*, which extend the entire length of the bottom and are perpendicu-

lar thereto. At either end of the buckle is a strap, *c*, across the end of the same. In the center of the bottom *a* is a pin, *d*, which projects slightly above the top of the sides *b*. 25

The face of the sides *b* and of the cross-strap *c* may be ornamented, as shown in the figures, by the representation of a branch; or the ornamentation may be left off, as I do not claim this. 30

Having described my new design for a buckle, what I claim is—

The design for a buckle, the same consisting of the bottom *a*, sides *b*, cross-plates *c*, and tongue *d*, as shown. 35

In testimony whereof I affix my signature in presence of two witnesses.

HENRY C. JOHNSON.
